UNITED STATES PATENT OFFICE

2,534,022

MANUFACTURE OF SALTS OF 2:1-
HYDROXYNAPHTHOIC ACID

Eric B. Higgins, Tewin Wood, England, assignor
to Tewin Industries Inc., county of New York,
N. Y.

No Drawing. Application March 31, 1949, Serial
No. 84,759. In Great Britain April 5, 1948

4 Claims. (Cl. 260—520)

1

This invention relates to the manufacture of salts of 2:1 hydroxynaphthoic acid and its object is particularly to enable the di-sodium salt of the acid to be produced in improved yield substantially free from material containing hydroxyl groups.

It has long been known that if carbon dioxide be allowed to react with dry sodium beta-naphtholate at temperatures of 120° C. to 140° C., good yields of 2:1 hydroxynaphthoic acid can be obtained according to the Kolbe reaction described in the specification of German Patent No. 426, as follows:

Practically quantitative yields, that is to say, 50 per cent upon the naphtholate employed are readily obtained if the naphtholate is subjected to the action of the carbon dioxide whilst in suspension in an agent, for example, toluene, at the boiling point of the liquid. (Oddo & Manuei, Gazzetta Chimica Italiana 31, II, 244, 1901.) It would seem clear, therefore, that if this latter method is adopted, as the liberated free beta-naphthol is freely soluble in toluene whereas the sodium hydroxynaphthoate is virtually insoluble, filtration of the mass and subsequent extraction with fresh solvent should provide a means of producing the disodium 2:1 hydroxynaphthoate substantially free from material containing free hydroxyl-groups.

In fact, however, it is found that great mechanical difficulties are encountered in such a process on account of the physical condition of the precipitated material, and moreover, the process does not, in fact, yield a product which can be relied upon not to contain free hydroxyl groups. This is doubtless due to the fact that both the starting material—sodium naphtholate, and the end product—sodium 2:1 hydroxynaphthoate are insoluble in the toluene, which militates against complete reaction, and that the reaction is not strictly confined to the route as given above, but can proceed according to either or both of the equations:

In fact, it has been found that at temperatures of 90–100° C., the reaction can proceed wholly according to the above Equation I, that is to say, the method of Schmidt, (Journal fur Praktische Chemie (2) 31, 397, 1885) and, moreover, without the necessity of employing superatmospheric pressures.

It has now been found that yields of disodium 2:1 hydroxynaphthoate, quantitative in respect

2

to the naphtholate used, can readily be obtained if the reaction between the dry sodium beta-naphtholate is a very suitable vehicle for this accordance with the present invention, in the presence of an additional equivalent quantity of free metallic sodium, thus:

The reaction is best carried out in a chemically indifferent liquid and, with the greatest advantage, if the liquid is a solvent for the naphtholate as well as for free beta-naphthol, and it has further been found by experiment that tetrahydronaphthalene is a very suitable vehicle for this purpose.

In order that the invention may be more clearly understood and readily carried into practice, various methods, will now be given by way of example.

20 *Example I*

In a vessel arranged to be heated and supplied with a reflux condenser and provided with a means of introducing carbon dioxide gas and, preferably, a stirrer or other means of agitation, 25 2000 litres of tetrahydronaphthalene are added to 144 kilograms of beta-naphthol, and 46 kilograms of sodium introduced. The air is preferably, though not necessarily, displaced from the apparatus by nitrogen or hydrogen or is evacuated, and, with stirring, the temperature is raised to the melting point of sodium at which point reaction becomes rapid, hydrogen being evolved. Stirring and heating must be carefully regulated 30 during the early stages so as to prevent the reaction from becoming too violent. The state of reaction can be judged by the evolution of hydrogen which accompanies it. As the evolution of gas slackens, the temperature is raised till the tetrahydronaphthalene is boiling, and the boiling 35 continued until the evolution of gas is complete or negligible. The reaction according to the equation:

40 is now substantially complete and the naphtholate forms a clear pale yellow solution. In these circumstances, the beta-naphthol is not hydrogenised to any significant extent. Carbon dioxide is then passed into the boiling solution, superatmospheric pressure being unnecessary. The hydroxynaphthoate begins at once to precipitate as it is practically insoluble in tetrahydronaphthalene and hydrogen is again evolved, according to the equation:

45 The duration of this stage of the reaction is mainly dependent upon the efficiency of the means used to ensure contact between the gas and

the reacting fluid. Simple bubbling of the gas through the liquid will produce the desired end, though slowly, but best results are realised if a cone or propeller type of stirrer is employed which forces the supernatant gas repeatedly through the violently agitated liquid. The end of the reaction can be ascertained by the cessation of evolution of hydrogen. The yield is substantially quantitative in respect to the beta-naphthol employed.

The product may be isolated by distillation of the solvent, preferably under sub-atmospheric pressure or by filtration or by centrifugal action, but air must at all times be rigidly excluded since the di-salt of 2:1 hydroxynaphthoic acid in the dry state is destructively oxidised with great ease.

Alternatively, the di-salt may be caused to enter into further desired reactions in suspension in the tetrahydronaphthalene without actual separation.

By conducting the second reaction at the boiling point of tetrahydronaphthalene, very small quantities of the 2:3 isomer may be formed. This may be wholly avoided by conducting the carboxylation at lower temperatures, for example 180 to 120° C. but the rate of reaction will be much reduced and, in such a case, it is preferable to use a higher proportion of solvent than that indicated at the beginning of this example.

Example II

In an apparatus as indicated in Example I, but with the addition of means for direct distillation, 144 kilograms of beta-naphthol, 40 kilograms of solid caustic soda in coarse powder and 3000 litres of tetrahydronaphthalene, are introduced. Air is removed or displaced from the apparatus and with constant stirring, the temperature is raised until distillation begins and the tetrahydronaphthalene-water azeotrope begins to distil according to the equation:

Distillation is continued until the distillate runs clear and the thermometer shows the boiling point of pure tetrahydronaphthalene. 23 kilograms of metallic sodium—conveniently previously melted under tetrahydronaphthalene is then added, the reflux condenser set in operation and treatment with carbon dioxide begun and carried through as described in Example I.

Example III

A quantity of the crude melt obtained in the manufacturer of beta-naphthol (which is essentially a mixture of sodium beta-naphtholate, caustic soda and sodium sulphite) containing naphtholate equivalent to 144 kilograms of beta-naphthol is extracted three times in sequence, in the absence of air, with 1000 litres of tetrahydronaphthalene at or near its boiling point. The filtered extract is transferred with protection from air to the apparatus as indicated in Example II, and the reaction then conducted as therein described.

Example IV

In an apparatus as indicated in Examples I and II, 72 kilograms of beta-naphthol is dissolved in 3000 litres of diphenylether ($C_6H_5)_2O$ and converted to the naphtholate either by the action of 16.5 kilograms of sodium according to the

method described in Example I or by reaction with 20 kilograms of caustic soda as explained in Example II. The solution is brought to a temperature of 98-100° C. and carbon dioxide gas introduced until no further absorption takes place. The reaction is slow and may occupy from 10 to 12 hours. At this stage the reaction, according to the equation:

is substantially complete. 16.5 kilograms of metallic sodium conveniently previously melted under di-phenylether is then slowly introduced with good stirring, keeping the temperature at 98-

15 100° C. Hydrogen is evolved and the di-sodium salt of 2:1 hydroxynaphthoic acid is produced according to the equation:

20 In all cases, the reaction is satisfactory and practical if conducted under atmospheric pressures but may be accelerated by increasing the solubility of CO_2 in the solvent by the use of super-atmospheric pressure should the corresponding

25 added mechanical complication of the apparatus be judged less significant. Sodium amalgam may be used instead of sodium metal but does not afford any chemical advantage.

I claim:

30 1. A process for the production of disodium 2:1 hydroxynaphthoic acid substantially free from material containing free hydroxyl groups which comprises heating sodium beta naphtholate in a chemically inert liquid to a temperature of between 98° C. and 210° C. in the presence of carbon dioxide and at least an equivalent quantity of metallic sodium.

2. A process according to claim 1, in which the chemically inert liquid is a solvent for beta-naphthol and the sodium derivative of the same.

3. A process for the production of disodium 2:1 hydroxynaphthoic acid substantially free from material containing free hydroxyl groups which comprises heating sodium beta naphtholate dissolved in diphenyl ether to a temperature of between 98° C. and 210° C. in the presence of carbon dioxide and at least an equivalent quantity of metallic sodium.

4. A process for the production of disodium 2:1 hydroxynaphthoic acid substantially free from material containing free hydroxyl groups which comprises heating sodium beta naphtholate dissolved in tetrahydronaphthalene to a temperature of between 98° C. and 210° C. in the presence of carbon dioxide and at least an equivalent quantity of metallic sodium.

Certificate of Correction

Patent No. 2,534,022

December 12, 1950

ERIC B. HIGGINS

It is hereby certified that error appears in the printed specification of the above numbered patent requiring correction as follows:

Column 2, line 3, for "naphthalene is a very suitable vehicle for this" read *naphthalate and carbon dioxide is carried out in*;

and that the said Letters Patent should be read as corrected above, so that the same may conform to the record of the case in the Patent Office.

Signed and sealed this 13th day of March, A. D. 1951.

[**SEAL**]

THOMAS F. MURPHY,
Assistant Commissioner of Patents.
